UNITED STATES PATENT OFFICE

149,053

DESIGN FOR A PLANT SUPPORT

Herman Epstein, Kansas City, Mo.

Application February 18, 1946, Serial No. 126,684

Term of patent 7 years

(Cl. D35—3)

To all whom it may concern:

Be it known that I, Herman Epstein, a citizen of the United States, residing at Kansas City, in the county of Jackson and State of Missouri, have invented a new, original, and ornamental Design for a Plant Support, of which the following is a specification, reference being had to the accompanying drawing, forming a part thereof.

Figure 1 is a front elevational view of a plant support showing my new design.

Fig. 2 is a plan view of the plant support as shown in Fig. 1.

Fig. 3 is a side view of the plant support; and

Fig. 4 is a plan view of the plant support as shown in Fig. 3.

I claim:

The ornamental design for a plant support, as shown.

HERMAN EPSTEIN.
